[57] CLAIM

The ornamental design for a shoe sole, as shown and described.

DESCRIPTION

FIG. 1 is a left side elevational view of a shoe sole showing my new design in a position of use;

FIG. 2 is a left side elevation view;

FIG. 3 is a bottom plan view;

FIG. 4 is a right side elevational view;

FIG. 5 is a top plan view;

FIG. 6 is a front elevational view;

FIG. 7 is a rear elevational view in vertical position; and,

FIG. 8 is a perspective view thereof.

The broken line showing of shoe upper in FIG. 1 is for illustrative purposes only and forms no part of the claimed design.
